UNITED STATES PATENT OFFICE.

FRANK STOCKDALE, OF LA GRANGE, ILLINOIS.

DESIGN FOR A DISPLAY STAND OR ARTICLE OF SIMILAR NATURE.

Application filed September 13, 1921. Serial No. 500,450. Term of patent 7 years.

To all whom it may concern:

Be it known that I, FRANK STOCKDALE, a citizen of United States, residing at La Grange, in the county of Cook and State of Illinois, have invented and produced a new, original, and ornamental Design for a Display Stand or Article of Similar Nature, of which the following is a specification, reference being had to the accompanying drawing, forming a part thereof.

The figure is a perspective view of a display stand showing my new design.

I claim—

The ornamental design for a display stand or article of similar nature as shown.

FRANK STOCKDALE.
